CLAIM

We claim the ornamental design of a remote control device,
as shown and described.

DESCRIPTION

FIG. 1 is a top, right, rear perspective view of a remote control device showing an embodiment of our new design; FIG. 2 is an exploded top, right, rear perspective view of the remote control device of FIG. 1;

FIG. 3 is a top plan view of the remote control device of FIG. 1;

FIG. 4 is a bottom plan view of the remote control device of FIG. 1;

FIG. 5 is a front elevation view of the remote control device of FIG. 1;

FIG. 6 is a rear elevation view of the remote control device of FIG. 1;

FIG. 7 is a left-side elevation view of the remote control device of FIG. 1; and,

(Continued)

FIG. 8 is a right-side elevation view of the remote control device of FIG. 1.

The broken lines in the drawings depict a portion of the remote control device that form no part of the claim.
